TYPOGRAPHICAL COMPOSING MACHINE

Richard Henry Scott, Enfield, and William Fairall Gorse and Arthur Staniland Hayward, Altrincham, England, assignors to Linotype and Machinery Limited, London, England, a British limited-liability company

Application May 6, 1939, Serial No. 272,210
In Great Britain May 11, 1938

11 Claims. (Cl. 199—11)

This invention relates to typographical composing machines of the kind employing circulating matrices which, by the operation of a keyboard, are released from magazines in which they are stored, and assembled in line, and wherein the assembled line is transferred from the assembler to a carrier or elevator by which the line is presented to a mould for the casting of a slug or type bar, the matrices and spacebands being subsequently transferred from the elevator to distributing mechanism by which they are restored to their appropriate magazine channels or magazine.

More particularly, the invention relates to the machines of this kind, wherein the composed line is transferred from the assembler to the elevator in a straight horizontal path, and wherein the elevator, which receives the line so transferred at the assembly level, conveys the line to a different level for casting and returns to the assembly level to discharge the used line and to receive a new line, the discharged line being taken by another organ of the machine for conveyance to or towards the distributing mechanism.

The object of the invention is to provide improved means for transferring the composed line from the assembler to the elevator and from the elevator to the distributor, to enable a high speed of composition to be maintained, by eliminating or substantially reducing periods during which operation of the keyboard must be interrupted during line transfers or owing to any of the successive organs of the machine not being in condition for the reception of a line in transit, and by reducing the interval of time between casting and distribution to ensure a speedy return of the matrices and spacebands to their respective magazines.

With these objects in view, a typographical composing machine according to the invention comprises a line-transfer box or carriage adapted to engage a completed line by moving downwardly into the assembler and thereafter to move horizontally to carry the line out of the assembler towards the elevator, and into the elevator when the latter is at the assembly level. The movement of the line into the elevator preferably also effects the ejection therefrom of the line previously cast.

A machine according to the invention further comprises a distributor conveyor including a plurality of line holders each adapted to receive a line discharged from the elevator at the assembly level and convey said line upwardly to the distributing mechanism, said conveyor being prefer-

ably endless and capable of intermittent movement in one direction so that as one line holder carries a line to the distributor another holder is brought into line-receiving relationship with the elevator at the assembly level.

Further features of the invention include key-actuated or automatically controlled means for initiating the movements of a line-transfer box or carriage, a line-resistant finger operating in the assembler and constituting part of the so-called assembler slide and means actuated on the downward movement of a line-transfer box, adapted to tilt said finger downwardly clear of the line to be transferred, said means also serving to control the return of the assembler slide and line resistant to their initial position ready for the assembly of a fresh line.

The invention is hereinafter more particularly described with reference to one constructional form thereof illustrated in the accompanying drawings, in which:

Figure 1 is a front elevation showing sufficient of a typographical composing and distributing machine to show the application of the present invention thereto;

Figure 2 is an elevation on an enlarged scale of the assembling mechanism;

Figure 3 is a plan view of the assembler slide and associated parts;

Figure 4 is a side elevation of the assembler and the mechanism illustrated in Figure 3;

Figure 5 is a side elevation, with portions broken away, of the distributor conveyor and operating means therefor;

Figure 6 is a front elevation of portion of the distributor conveyor showing a line holder in line-receiving position;

Figure 7 is a plan view of one of the line holders;

Figure 8 is a front elevation of the devices for transferring the line to the distributor showing a line holder in the line-delivering position;

Figure 9 is an elevation, partly in section, of the line-transferring mechanism illustrated in Figure 8; and

Figure 10 is a detached view, inside elevation showing means for operating the assembler and distributor transfer slides.

The drawings show the invention as applied to a machine which, so far as its general construction is concerned, is of the kind known commercially under the registered trade-mark "Linotype." For this reason it is deemed unnecessary herein to more particularly describe or illustrate in detail those parts which are, or may be, sub-

5

55

stantially identical with or similar to those of well-known machines of the said kind. The relevant parts of such a machine, however, are shown in Figure 1, from which it will be recognized that 5 matrices X (Figure 9), and spacebands Y (Figure 8), are composed in line in an assembler 1 and stacked therein by a star wheel 4, against a line 10 resistant 5 carried by an assembler slide (hereinafter designated as a whole by the reference 15 numeral 7) and spacebands in the usual manner, held yieldingly against the leading matrix of an 20 assembling line by a spring 8 acting on the assembler slide 7, which latter, as also is usual, is provided with a brake 9 which permits advancing 25 movement of the slide and prevents its backward 30 movement during line assembly. After assembly the line is transferred by a transfer carriage lever 44 which acts in known manner to move the line into the elevator 57^a by which the line is presented 35 to the casting mechanism. Subsequently the line is conveyed to the distributing mechanism, the matrices delivered to a lift box 66 and the spacebands to their magazine 65.

For the purposes of the present invention the 23 assembler 1 is in the form of a fixed horizontal guideway formed with rails 2, 3, to support the 28 matrices, the assembler slide 7 is divided lengthwise into two portions 6, 7, as shown best in Figure 2, and the leading portion 6, which carries 33 the resistant finger 5, is pivotally connected to the following portion 7 so that it may be swung 38 downwardly to remove the resistant finger 5 from the assembler 1. The forward end of the leading portion 6 is normally supported on an underlying 43 retractile roller 10, and the rear end of the said portion 6 is provided with a downwardly extending 48 bracket 11, which is pivotally mounted at 12 on a bracket 13 extending downwardly and forwardly from the leading end of the following portion 53 7.

A roller 14 concentric with the pivot 12, and running in a fixed guideway 15, serves as a support for the adjacent ends of the two assembler slide portions throughout the longitudinal movement of the slide. An arm 16 extends downwardly from the pivot 12 of the leading portion 6 and is connected to a block 17 on a control rod 18 which serves to control the pivotal movement of the said portion 6, as hereinafter described, and a spring 19 acting between the leading and following slide portions tends constantly to maintain the leading portion 6 in its horizontal operative position.

The following portion 7 of the assembler slide 58 is provided on its underside with a rack 20 adapted to be engaged by an assembler slide locking pawl 21, mounted on a fixed pivot 22 and normally held by its own weight out of engagement with the rack 20. This pawl 21 is also formed with an extension 23 which co-operates with an assembler slide-brake trip lever 24 to effect release of the brake 9 when the pawl 21 is moved into engagement with the rack 20.

The above-mentioned control rod 18 (see Figures 3 and 4) lies below and at the rear of the assembler slide, parallel thereto, and is slidable longitudinally in fixed guides 25, to effect tilting of the assembler slide portion 6, as hereinafter described. The block 17 on the control rod 18, has pivoted to it at 28, a pawl 26 which can be engaged with a rack 27 on the rod 18, but is normally held out of such engagement, as shown in full lines in Figure 3, by a bar 31, lying parallel with the rod 18, bearing against a roller 30 on an arm of the pawl and resisting the action of a

spring 29 constantly tending to move the pawl 26 to the position in which it is shown in dotted lines in the said figure, i. e., into engagement with the rack 27. The bar 31 is mounted for parallel motion away from and towards the control rod 18, being pivoted at one end to an arm 54 by which it is operated as hereinafter described, and guided at the other end by a roller 62 running in a slot 63 in a fixed bracket 64. Thus, during the assembly of a line, owing to the action of the bar 31 and the connection of the block 17 to the arm 16, the said block 17 moves leftward, as viewed in Figures 1, 2 and 3, along the rod 18, accompanying the movement of the assembler slide 6 in the same direction. The rod 18 is further provided with a rigid arm 32, which on longitudinal movement of the rod 18, actuates the assembler slide locking pawl 21.

The line transfer device, in the present constructional form of the invention (see particularly Figures 2 and 3), is in the form of a carriage 33 having depending fingers 34, 35, for engaging opposite ends of the assembled line, which is laterally slidable in a horizontal guide 36 vertically movable in a guide 37. In the normal rest position in which it is represented in the drawings, the line transfer carriage 33 is located above the assembler 1 and the carriage guide 36 is in its upper position, in which it is retained by a spring catch 38 which can be actuated by a lever 39 (which may be controlled by a finger key or automatically, e. g., by a perforated tape) to release the carriage guide 36. On the descent of the latter, a pivoted latch 40 mounted thereon and retaining the carriage 33 in its rightmost position, is released by an adjustable stop 41 (secured to the stationary vertical guide 37) engaging a rod 42 connected with the latch, to permit the carriage to move leftward under the action of a spring 43, acting through lever 44 and link 45. The return movement of the transfer slide is effected in known manner by a cam on the main cam shaft acting on the lever 44.

During the descent of the guide 36, the above-described assembler slide control mechanism is actuated through the movement of a lever 46 controlled by a link 47 depending from the carriage guide 36. For this purpose one arm of the actuating lever 46 extends into the downward path of the said link 47 and its other arm is arranged to swing between two arms 48, 49, respectively, secured to vertical rock shafts 50, 51, at the rear of the assembler (see Figures 3 and 4). These two arms 48, 49, are hereinafter termed the bar operating arm and the control rod operating arm respectively. The shaft 50 to which the bar operating arm 48 is secured, also carries a second arm 52 connected by a link 53 to the retractile assembler slide supporting roller 10, and a third arm 54 pivotally connected to the parallel motion bar 31. A spring 55 acting preferably on the arm 54, constantly tends to move the bar operating arm 48 towards the actuating lever 46, such movement being normally prevented by a stronger spring 56 acting on said lever 46. The shaft 51 of the control rod operating arm 49 carries a second arm 57 having a pin and slot connection with the control rod 18. Hence, when the actuating lever 46 is moved by the link 47 on the descent of the line carriage 33, against the action of the spring 56, the bar operating arm 48 urged by the spring 55 follows the actuating lever 46 during the initial movement of the latter, and thereby the assembler slide supporting roller 10, through the link 53, is retracted from its oper-

ative position and the bar 31 is actuated to permit the spring 29 and pawl 26 to lock the block 17 to the control rod 18. Immediately thereafter the actuating lever 46 contacts with the control rod operating arm 49 and moves the control rod rightwardly longitudinally. This longitudinal movement first actuates the slide locking pawl 21, by means of the arm 32, to lock the rear portion 7 of the slide against return movement, and to release the slide-brake 9. Continued movement of the control rod 18 in the same direction serves, through the movement of the block 17 with the rod, to turn the assembler slide portion 6 downwardly about its pivot 12, thereby removing the line-resistant 5 from the assembler 1. As the resistant 5 reaches its inoperative position, the above-mentioned catch 40 releases the carriage 33 which then carries the line out of the assembler towards the elevator 57^a. The line may be conveyed directly into the elevator, or in the event of the elevator not being in position to receive the line, the carriage may be arrested in known manner against a stop which is thereafter released by the presentation of the elevator to its line-receiving position.

The travel of the carriage 33 towards the elevator 57^a (towards the left in Figure 2) is utilised to release the actuating lever 46 and thereby to bring about the return movement of the control rod 18 and parallel motion bar 31 to re-set the assembler slide 7 for the composition of a new line. To this end the link 47 depending from the carriage slide is formed with an upwardly extending head having an arcual slot 58 engaged by a pin 59 on the slide, and this depending portion is guided for vertical and pivotal movement by a pin 60 on the machine frame engaging a vertical slot 61 in the link. A spring 68 is provided to constantly urge the link towards the operative position with one end of the slot 58 bearing against the pin 59. A tumbler 67 pivoted on the slide and prevented from swinging anti-clockwise by a stop pin 135 is positioned to engage with a pin 136 on the head of the link 47, during the leftward travel of the carriage 33, and thus swing the lower end of the link 47 out of operative relationship with the lever 46, as indicated in dotted lines in Figure 2.

The constructional form of distributing mechanism illustrated in detail in Figures 5 to 9 of the drawings, comprises an endless chain conveyor 70 which carries a plurality of line holders 69, passed around sprocket wheels 118 and is intermittently moved to effect presentation of one line holder at assembler level and another line holder at the distributing level. There are preferably three line holders spaced equidistantly along the chain, each line holder being pivotally supported on a block or plate 71 connected to a link of the conveyor. Each line holder comprises rails 72 (Figure 7) for supporting the lugs of the matrices and spacebands respectively, and also a line resistant 73 frictionally fitting between the rails to hold a line in any position to which it is pushed on transfer from the elevator. Each holder further comprises a tail-piece 74 carrying a roller 75 positioned to engage, during the movement of the conveyor, fixed cams 76, controlling the position of the holders. The cams 76 may be arranged to sustain each holder at the line-receiving station A slightly inclined downwardly from the receiving end at the assembler level, as shown best in full lines in Figure 6, and in a horizontal position at the distributing station B for the delivery of the line to the distributor (see the

full line position in Figure 8), while at an intermediate station C each holder will be sustained in a position substantially parallel with the conveyor.

On arriving at the distributing station B each holder is brought into horizontal alignment with a set of distributor approach rails 77 arranged to support the matrices and spacebands by their ears during transit of the line out of the holder and towards the distributor, which transit is effected by an automatically operated rake arm 78 which sweeps the line along the distributor approach rails 77 to a position beyond a gap 79 in the said rails. A ribbed V-bar section 80 is located above the gap 79 for supporting the matrices by their teeth during their passage over the gap; at this point, therefore, the spacebands are released from the rails into an auxiliary spaceband magazine 81 from which they are subsequently released into a channel 82 and thereby conducted to the usual spaceband magazine 65.

It may be here mentioned that the use of the auxiliary spaceband magazine 81 is desirable in view of the possibility of a number of spacebands being delivered in rapid succession from the approach rails, in which case they would not satisfactorily follow one another down the channel 82. As shown in Figure 8, the spacebands are preferably released from the auxiliary magazine 81 by an escapement 97 of known form operated by a lever 98 and link 99 connected to the matrix lifter lever 100 the latter being operated in known manner to raise the matrices from the distributor box 66 on to the distributor screws. On leaving the channel 82 the spacebands are, in the constructional form illustrated, received between adjacent flights of travelling belts 101 which guide them on to a chute 102 moving to the usual spaceband magazine 65.

At the completion of the inward stroke of the rake arm 78 it reaches the position in which it is shown in dotted lines in Figure 1, the matrices then being stationary on the approach rails 77, between the gap 79 and the distributor lift box 66. The rake arm 78 is then returned to its rest position, shown in full lines at the left of Figures 1 and 8, ready for the transfer of the next line, and a pusher arm 83 comes into action on the line sustained by the approach rails to further advance the line therealong to the distributor box 66 by which the matrices are presented to the distributing mechanism.

The rake arm 78 is preferably pivotally mounted on a slide 85 which reciprocates horizontally in a fixed guide 86 above the approach rails, and arranged to be automatically rocked into and out of operative position at the respective ends of the stroke of the slide. For this purpose the rake arm 78 carries a roller 87 which runs in a track 88 at the inner end of which, i. e., the end nearest to the distributor, there is provided a hinged flapper 89 which is lifted by the roller 87 just before the slide reaches the end of the inward stroke, so that at the commencement of the outward stroke the roller 87 runs up the flapper 89 on to a rail 90 above the track 88. At the outer end a cam 90 allows the rake arm 78 to again drop to the operative position with the roller 87 aligned with the track 88.

The pusher arm 83 may be similarly operated. It is carried on a slide 91 and has a roller 92 running inwardly on a rail 94 and outwardly in a track 93 beneath the rail. At the outer end of the track a flapper plate 96 controls the raising of the arm 83 and at the inner end a spring-

controlled flapper plate 95 guides the roller 92 into the track 93 at the commencement of the outward stroke. Figure 1 shows the extreme positions of the rake arm 78 and pusher arm 83 in full lines and in dotted lines respectively. The timing of the operations of the two arms in relation to the conveyor movements is arranged so that the rake arm 78 is always ready to discharge a line from a line-holder 69 reaching the distributing station B, while a pusher arm 83 acts on the preceding line until all the matrices thereof have been delivered to the distributor. The slides 85 and 91 are independently operated by mechanism shown in Figure 1 and now to be described.

15 The rake arm slide 85 is engaged by the upper arm of a lever 103 pivoted on a shaft 104 and having another arm 105 connected by a link 106 to a lever 107 operated by a cam 108. A spring 109 anchored to the machine frame D, and acting on the lever 103 serves to effect the outward movement of the slide 85, the inward movement thereof being controlled by the cam 108. The cam 108 also serves to effect the return to line-receiving position of the line resistant 73 in the line holder 69 for the time being at the intermediate station C, through the actuation of a finger 131 rocking freely on a fixed stud 132. A toothed segment 133 carried by the finger 131 meshes with a segment 134 operatively fast to

20 the rake arm lever 103; hence, when the cam moves said lever inwardly the finger 131 is rocked downwardly to engage the resistant 73 and sweep it along the holder.

25 30 35 30 35 40 45 50 55 60 65 70 75 75 80 85 90 95 100 105 110 115 120 125 130 135 140 145 150 155 160 165 170 175 180 185 190 195 200

30 The pusher arm slide 91 is operated by link 110 and lever 111 pivoted on the before-mentioned shaft 104 and having a segmental gear arm 112 in mesh with a gear segment on one arm of a lever 113, the other arm of which is engaged by a cam 114. A spring 115 anchored to the machine frame D and acting on the lever 111 serves to hold the lever 113 in contact with the cam 114, the slide 91 thus being spring-operated inwardly and cam-operated on the outward stroke.

45 50 55 60 65 70 75 80 85 90 95 100 105 110 115 120 125 130 135 140 145 150 155 160 165 170 175 180 185 190 195 200

55 The cams 108 and 114 are carried on a vertical cam shaft 116 which is operated by bevel gears 137, 138, from the main cam shaft 117, as shown in Figure 10. The means for returning the line transfer carriage guide 36 to its normal position are also illustrated in Figure 10. Said means consist of a cam 139 on the main cam shaft 117 and a lever 140 connected to the upwardly extending portion of the guide. It will be understood that the downward movement of the guide 36 is by gravity, when the latch 40 is released.

60 Intermittent motion of the conveyor 70 is also derived from the last-mentioned cam shaft 117 as illustrated in Figure 5, the lower sprocket wheel 118 around which the conveyor chain is guided being driven by a gear 119 in mesh with a pinion 120 which is in turn driven in one direction only through a free wheel 121 in mesh with a rack 122 which is reciprocated by a link 123 and lever 124 held by a spring 125 in contact with a cam 126. The rack 122 is guided by a roller 127 and slotted guides 128. A ratchet wheel 129 operatively fixed to the gear 120 operating with a spring pawl 130 ensures that the sprocket 118 will be operated during only the outward cam-controlled stroke of the rack 122.

65 In the constructional form of machine illustrated, the elevator 57a has a cam controlled movement downwardly to the casting mechanism and upwardly to the line-receiving position, it being understood that these movements, as well

70 as the movements of other organs of the machine, with which the present invention is not specifically concerned, and which, therefore, are not described in detail, are controlled automatically in the usual manner by cams or gears from the main cam shaft 117.

75 It should be noted that the introduction of the line into the elevator is, in the apparatus illustrated, accompanied by the ejection therefrom of the previously composed line, the travel 10 of the transfer carriage 33 being made to serve the dual purpose, and that as the elevator descends to the casting position the carriage guide 36 is raised and the carriage 33 returned to its waiting position above the assembler. It is also 15 to be noted that the particular constructional forms of the device hereinbefore described are given merely as examples and that alternative constructional forms may be employed in carrying the invention into effect.

20 Having described our invention, we declare that what we claim and desire to secure by Letters Patent is:

25 1. In a typographical composing machine, the combination with a fixed assembler in which 25 matrices are composed in line, of a pair of line-transfer fingers movable downwardly into the assembler to embrace a line therein and laterally to carry the line out of the assembler.

30 2. In a typographical composing machine, the 30 combination with a fixed assembler in which matrices are composed in line, and a resistant located in the assembler adapted to yield against a line advancing in the assembler, of a pair of line-transfer fingers movable downwardly into 35 the assembler to embrace a line therein and laterally to carry the line out of the assembler and means controlled by the descent of the line-transfer carriage adapted to remove the resistant from the assembler.

40 3. In a typographical composing and line casting machine, the combination with a fixed assembler in which matrices are composed in line, an elevator in which a composed matrix-line is presented to a casting mechanism, a distributing 45 mechanism to which a composed matrix-line is delivered after casting and a conveyor adapted to carry a composed line directly from the elevator to the distributing mechanism, of a line-transfer carriage movable laterally to carry a 50 composed line from the assembler to the elevator and operative simultaneously to carry a previously composed line from the elevator to the conveyor.

4. In a typographical composing and line casting machine, a combination according to claim 3, 55 characterised by an endless conveyor comprising a plurality of line holders, and means adapted to move said conveyor intermittently to carry the line holders in succession from a line receiving 60 station to a distributing station.

5. In a typographical composing and line casting machine, a combination according to claim 3, characterised by an endless conveyor comprising a plurality of line holders, each 65 embodying a line resistant slidable therein during the insertion of a line, means adapted to move said conveyor intermittently to carry the line holders in succession from a line receiving station to a distributing station and to an intermediate station, and means operable on a line holder at the intermediate station to return the line resistant to the line-receiving position.

70 75 80 85 90 95 100 105 110 115 120 125 130 135 140 145 150 155 160 165 170 175 180 185 190 195 200

6. In a typographical composing machine, the combination with a fixed assembler in which 75

5 matrices are composed in line, and a resistant located in the assembler adapted to yield against a line advancing in the assembler, of a pair of line-transfer fingers movable downwardly into the assembler to embrace a line therein and laterally to carry the line out of the assembler, means controlled by the descent of the line-transfer fingers adapted to remove the resistant from the assembler and means controlled by the 10 lateral movement of the line-transfer fingers adapted to return the line resistant to operative position in the assembler.

7. In a typographical composing and line casting machine, a combination according to 15 claim 3, characterised by an endless conveyor comprising a plurality of line holders, means adapted to move said conveyor intermittently to carry the line holders in succession from a line-receiving station to a distributing station and to 20 an intermediate station, and means operable during the movement of the conveyor to guide each line holder to an inclined position at the receiving station, a horizontal position at the distributing station and a substantially vertical 25 position at the intermediate station.

8. In a typographical composing and line casting machine, a combination according to 30 claim 3, characterised by an endless conveyor comprising a plurality of line holders, means adapted to move said conveyor intermittently to carry the line holders in succession from a line receiving station to a distributing station, means operable at the distributing station to carry a line out of a holder towards the distributor, 35 and means operable to separate spacebands from matrices in the line during the movement of the line towards the distributor.

9. In a typographical composing and line casting machine, a combination according to 40 claim 3, characterised by an endless conveyor comprising a plurality of line holders, means adapted to move said conveyor intermittently to carry the line holders in succession from a line receiving station to a distributing station,

means operable at the distributing station to carry a line out of a holder towards the distributor, means operable to separate spacebands from matrices in the line during the movement of the line towards the distributor and means operable to continue the movement of matrices towards the distributor after the separation of the spacebands therefrom. 5

10. In a typographical composing and line casting machine, a combination according to 10 claim 3, characterised by an endless conveyor comprising a plurality of line holders, means adapted to move said conveyor intermittently to carry the line holders in succession from a line receiving station to a distributing station, means 15 operable at the distributing station to carry a line out of a holder towards the distributor, means operable to separate spacebands from matrices in the line during the movement of the line towards the distributor, an auxiliary spaceband magazine adapted to receive the spacebands thus separated, automatically operating escapement mechanism adapted to release spacebands individually from said auxiliary spaceband magazine, and a chute adapted to conduct spacebands so released to a main spaceband magazine. 20

11. In a typographical composing machine the combination with a fixed assembler in which matrices are composed in line, a resistant located in the assembler, an assembler slide comprising a leading portion carrying said resistant pivotally attached to a following portion, of a pair of line transfer fingers movable downwardly to embrace a line therein and laterally to carry the line out of the assembler, means controlled by the descent of the line transfer fingers adapted to lower the leading portion of the assembler slide, and means controlled by the lateral movement of the transfer fingers to raise said leading portion and restore the resistant and slide to 30 the line receiving position. 35
